UNITED STATES PATENT OFFICE.

GEORGE TICKNER, JR., OF LONDON, ENGLAND.

PASTING APPARATUS FOR CIGARETTE-MACHINES.

No. 856,823.

Specification of Letters Patent.

Patented June 11, 1907.

Application filed August 9, 1906. Serial No. 329,938.

To all whom it may concern:

Be it known that I, GEORGE TICKNER, Jr., a subject of the King of Great Britain, of 33 and 35 Endell street, London, in the county 5 of Middlesex, England, have invented new and useful Improvements in Pasting Apparatus for Cigarette-Machines, of which the following is a specification.

My invention relates to improvements in 10 apparatus for gumming or pasting the edge of paper for manufacturing cigarettes, in which one edge of a roll of paper of the necessary width is fed continuously forward, and has one of its edges automatically gummed 15 or pasted as it travels along, and the objects of my improvements are, first, to provide means for automatically applying gum or paste perfectly uniformly and evenly to the edge of the paper; second, to provide means 20 for triturating the gum or paste and freeing it from lumps and reducing it to a perfectly even and smooth condition before it is applied to the edge of the paper; and third, to provide means for accurately adjusting 25 the parts of the apparatus by which the trituration of the gum or paste and its application to the edge of the paper is effected. I attain these objects by the mechanism illustrated in the accompanying drawings, in 30 which:—

Figure 1 is a side elevation, partly in section, of the improved pasting apparatus. Fig. 2 is partly a transverse section through the end of the cylinder, and partly an end 35 view. Fig. 3 is a plan of the apparatus. Fig. 4 is a front view on a larger scale, of the upper disk, and Fig. 5 is a side view of the same.

The same letters of reference indicate similar parts in the different views.

a is a horizontal tube carried upon the frame *b*.

c is a piston or plunger fitting in the tube *a* and forced forward by the toothed rack *d* and toothed pinion *e* in the manner described in the specification of my former Letters Patent, dated August 14th 1906, No. 828,786.

f is a strong end cover to the cylinder *a*, 50 having a recess *g* in which fits closely but freely the disk *h*. In a central hole *i* in said cover fits a hollow trunnion *j* having longitudinal curved recesses *k* at its sides, as shown in Figs. 4 and 5.

f' is a downward extension of the cylinder end *f* in which is formed a second recess *g'*

similar to the upper one *g*. A second disk *h'* fits closely but freely in the recess *g'* in which it can revolve.

l is an outer cover fitting over both the 60 recesses *g* and *g'*, an opening between the recesses allowing the peripheries of the disks *h* and *h'* to touch as they revolve (as shown in Fig. 2).

m is a spindle passing through the outer 65 cover *l* and having fixed upon its inner end the disk *h*, and the short recessed cylinder *j*. A second spindle *n* parallel to the spindle *m* passes through the outer cover *l*, the disk *h'*, and the cylinder end *f'* and is continued to a 70 bearing *o* at the other end of the supporting frame *b*, in which it is made to revolve by a toothed wheel *p* gearing with any suitable part of the cigarette-making machine.

r, *r'* are toothed wheels by which the spindles *m*, *n*, are coupled together, and *s* is a thumb screw mounted in a bracket *s'*, and bearing against the end of the spindle *m*, so that by turning said screw the spindle *m* will be moved to adjust the grooved face of the 80 disk *h*, with relation to the wall of the recess *g*. As shown in Figs. 4 and 5 the upper disk *h* is dished or hollowed at *t* on its front surface, and the surface of this dishing is in the form of radial grooves extending from near 85 the center to near the circumference (as illustrated in Fig. 4).

u is a thin horizontal disk upon a vertical spindle *v* carried in the adjustable support *w* and set in revolution by a pulley *x* driven by 90 a cord or belt *y*. The edge of this disk *u* passes through the narrow opening *u'* at the side of the lower recess *g'*, and receives upon its edge the paste from the disk *h'*. The edge of the paper strip which is to be pasted is fed 95 along against the periphery of the thin disk *u* the upper edge of which is rounded, (as shown at *z* Fig. 2) and receives from the latter a continuous and even narrow line of paste along its edge.

The rack *d* is forced forward by a pinion *e*, and the pressure upon the piston *c* is regulated by means of a brake wheel, and a strap the tension of which is adjusted by a spring regulated by a screw, these devices being 100 similar to those described and shown for the same purpose in the specification of my said former Letters Patent, dated August 14th, 1906, No. 828,786.

When this apparatus is in operation the 110 paste (or other suitable material) with which the tube *a* is filled, is forced, by the pressure

of the plunger *c* in the tube *a*, through the opening *i* in the cylinder end *f*, and along the curved recesses on the short revolving cylinder *j* into the center of the radial recesses 5 on the dished front of the disk *h* upon the spindle *m*. The paste is thoroughly triturated and ground between the face and periphery of the disk *h*, and the corresponding wall and periphery of the recess *g*, the space 10 between the peripheries being just sufficient to allow the finely mixed and smooth paste to pass, and the said space between the face of the disk *h*, and said wall being accurately adjustable by the screw *s*. The paste so 15 treated is transferred to the periphery of the second, or lower, disk *h'*, through the opening between the adjoining recesses *g* and *g'*, and is taken off from the last named disk by the edge of the thin disk *u* which presses against 20 *h'* through the opening in the side of the recess *g'*, and thence to the edge of the paper.

The details of construction, and the relative proportions of the several parts may be varied more or less, as may be found advisable.

What I claim as my invention and desire to secure by Letters Patent, is:—

1. In an apparatus for pasting a continuous strip of paper, the combination with the 30 paste receptacle, of a driving spindle mounted adjacent said receptacle, a driven spindle, gears connecting said spindles, disks mounted on said spindles and adapted to rotate in close peripheral engagement, means for feeding the paste between said disks, and a paste applying disk adapted to receive the triturated paste from one of said engaging disks, and transfer the same to the strip of paper, substantially as described.
2. In an apparatus for pasting a continuous strip of paper, the combination with a cylindrical paste chamber, of a pair of parallel spindles mounted adjacent said chamber, disks mounted on said spindles and adapted to rotate in close peripheral engagement, means for forcing the paste between the peripheries of said disks, and a paste applying disk adapted to receive the triturated paste from one of said triturating disks and transfer the same to the strip of paper, substantially as described.
3. In an apparatus for pasting a continuous strip of paper, the combination with the paste receptacle, of a driving spindle mounted adjacent said receptacle, a driven spindle, gears connecting said spindles, disks mounted on said spindles and adapted to rotate in close peripheral engagement, means for adjusting said disks, means for feeding the 55 paste between said disks, and a paste applying disk adapted to receive the triturated paste from one of said engaging disks and transfer the same to the strip of paper, substantially as described.

4. In an apparatus for pasting a continu-

ous strip of paper, the combination with a cylindrical paste chamber, of a pair of parallel spindles mounted adjacent said chamber, disks mounted on said spindles and adapted to rotate in close peripheral engagement, 70 means for forcing the paste between the peripheries of said disks, means for adjusting one of said disks, and a paste applying disk adapted to receive the triturated paste from one of said triturating disks and transfer the 75 same to the strip of paper, substantially as described.

5. In an apparatus for pasting a continuous strip of paper, the combination with a cylindrical paste chamber, of a pair of parallel spindles mounted adjacent said chamber, disks mounted on said spindles and adapted to rotate in close peripheral engagement, 80 means for forcing the paste between the peripheries of said disks, means for adjusting one of said disks, a vertical spindle mounted adjacent said disks, means for adjusting said spindle, and a paste applying disk mounted on said spindle and adapted to receive the triturated paste from one of said triturating 85 disks and transfer the same to the strip of paper, substantially as described.

6. In an apparatus for pasting a continuous strip of paper, the combination with a cylindrical paste chamber, a plunger operating therein to force forward the paste, a hollow cylinder head provided with an opening opposite the paste chamber, a pair of spindles mounted adjacent said cylinder head, disks mounted on said spindles in the hollow 95 100 of said cylinder head and adapted to rotate in close peripheral engagement, a grooved trunnion carried by one of said disks and adapted to rotate within the opening in said cylinder head, said disk being also provided with radially extending slots adapted to admit the paste between the peripheries of said 105 rotating disks, and a paste applying disk adapted to receive the triturated paste from one of said triturating disks and transfer the 110 same to the strip of paper, substantially as described.

7. In an apparatus for pasting a continuous strip of paper, the combination with a cylindrical paste chamber, of a plunger working 115 therein to force forward the paste, a pair of parallel spindles mounted adjacent said chamber, disks mounted on said spindles and adapted to rotate in close peripheral engagement, means for admitting the paste between the peripheries of said disks, means for adjusting one of said disks, a vertical spindle mounted adjacent said disks, means for adjusting said spindles, and a paste applying disk mounted on said spindle and adapted to receive the triturated paste from one of said triturating disks and transfer the 120 125 same to the strip of paper, substantially as described.

8. In an apparatus for pasting a continu-

ous strip of paper, the combination with a cylindrical paste chamber, of a plunger working therein to force forward the paste, a hollow head attached to the end of said cylinder, 5 a pair of parallel spindles mounted adjacent said cylinder head, disks mounted on said spindles in the hollow of said cylinder head and adapted to rotate in close engagement, means for admitting the paste between the 10 peripheries of said disks, means for adjusting said disks, a vertical adjustable spindle mounted adjacent said disks, a paste applying disk mounted on said spindle, said cyl-

inder head being provided with an opening, adjacent one of said rotating disks, through 15 which said paste applying disk is adapted to project and to receive the thoroughly smooth and triturated paste and transfer the same to the paper strip, substantially as described.

In witness whereof I have hereunto set my 20 hand in the presence of two witnesses.

GEORGE TICKNER, JNR.
